Atty.

UNITED STATES PATENT OFFICE

HARRY B. BALTHASER, OF PHILADELPHIA, PENNSYLVANIA

SURGICAL CLAW SCISSORS

Application filed September 22, 1930. Serial No. 483,433.

My invention relates to new and useful improvements in surgical claw scissors, and has for one of its objects to so fashion the blades as to provide hook or claw-like cutting edges which will prevent the scissors slipping off the object being cut or said object slipping out from between the blades as often occurs where straight blade scissors are used.

Another object of the invention is to so construct the blades that all sharp points are eliminated and so that the cutting edges are back of the forward or outer ends of the blades whereby the forward or outer end of said blades act as a guard for the cutting edges when the scissors are inserted to carry out an operation.

A further object of the invention is to provide a pair of surgical scissors, both blades of which are identical in construction but in reversed relation, said blades having relatively short cutting edges with curved portions terminating short of the outer ends of the blades and since the cutting edges terminate short of the outer ends of said blades, the latter act as guards and the curved portions prevent slipping of the work or scissors relative to each other during the cutting operation.

A still further object of the invention is to provide a pair of scissors for use in surgery and particularly veterinary surgery in which both blades are cross-shaped and the termini are rounded to prevent injury to organs of human or animal bodies.

With these ends in view, this invention consists in the details of construction and combination of elements hereinafter set forth and then specifically designated by the claims.

In order that those skilled in the art to which this invention appertains may understand how to make and use the same, I will describe its construction in detail, referring by numerals to the accompanying drawing forming a part of this application, in which:

Fig. 1, is a face view of a pair of scissors constructed in accordance with the invention and shown in a closed position.

Fig. 2, is a similar view in an open position.

In carrying out the invention as herein embodied, 5 and 6 represent the blades of a pair of scissors pivoted at any suitable place intermediate their ends as indicated at 7 and provided with a handle 8 and 9 of any desirable shape, construction or configuration. Each blade has a falcated notch or recess 10 formed in what I call the inner edge and the edge around said falcated recess is sharpened or beveled to provide a cutting edge having a substantially straight portion extending obliquely from the inner side edge of the blade to a point within the body of the blade adjacent its outer end, a curved portion and another short substantially straight portion leading back to the inner side edge of the blade.

The falcated recess in the edge of a blade produces a claw or hook 11, the terminal of which is rounded as indicated at 12 so as to eliminate any sharp point which might injure organs surrounding the one on which an operation is being performed or even which might prematurely puncture the organ to be operated.

What might be said to be the primary advantage in constructing a pair of scissors in the manner above described is that said scissors will cut just that part which you want to cut without cutting or injuring anything else or disturbing any other tissue or contiguous organs. The cutting blade being short and small, when it is desired to cut a tendon or ligament, the cutting edges of the scissors are simply placed around the object and the scissors closed in the ordinary manner and since the claws or hooks first close about the object, the latter cannot slip out or become disengaged from the blades and only the surrounded object will be cut.

A pair of scissors of this kind can be used for cutting many different kinds of tissues and parts of a body, such as muscle, tendon, ligament, cartilage, nerve, blood vessel and other similar objects with a single operation of the scissors which in many cases cannot be accomplished with ordinary surgical scissors.

As an example of the usefulness and advantages of a pair of scissors of this kind, it will be assumed that a hanging tumor is to be removed from the abdomen. As soon as the tumor is located, it is tied off, usually with cat gut, and the scissors can be inserted in a closed condition until the ends of the blades impinge upon the tumor. The scissors are then opened and the ends of the blades passed around the tied part of the tumor. Since the cutting edges are located back of the ends of the blades and within the body thereof, the ends of said blades act as guards during the insertion of the scissors and also during the time they are passed about the tumor.

As soon as the claw ends of the blades are around the tumor, the scissors are operated to cut off the tumor and during the cutting operation, there is no chance of cutting or otherwise damaging bowels or organs nearby and since the tumor cannot become dislodged from the cutting edges due to the claw ends the single cutting operation will complete the work expeditiously.

Scissors of this kind are also very useful in cutting ingrown toenails of animals because they may be cut off with a single operation at great speed and in a positive manner so that a second operation is never necessary and therefore the animal is practically undisturbed. Ingrown toenails are painful and an animal will not permit the making of a number of cuts unless an anesthetic is used, but with the use of scissors constructed as above described, the operation is so quick that it is over by the time the animal is aware that the nail has been touched.

Of course I do not wish to be limited to the exact details of construction as herein shown, as these may be varied with the limits of the appended claims without departing from the spirit of my invention.

Having thus fully described my invention, what I claim as new and useful is:—

1. In surgical scissors, a pair of blades pivotally connected to one another and each having a cutting edge projecting in a substantially straight line from the inner edge of the blade toward the outer edge and toward the outer end of said blade and then extending in a curved line still toward the outer end of the blade back toward the inner edge thereof with a short straight portion between the curved part and said inner edge contiguous to the outer end of the blade and with said outer end forming a claw having a blunt terminal.

2. Surgical scissors including a pair of blades, both having identical falcated cutting edges extending over the entire operating length of the blades with the hooked portions terminating at the extreme outer ends of said blades, and the outer end edges of the blades

being rounded whereby the termini of the hooked portions lie inside of the extreme outer ends of the blades.

In testimony whereof, I have hereunto affixed my signature.

HARRY B. BALTHASER.
